UNITED STATES PATENT OFFICE

2,468,191

MULTISCALE RULE

Dixie L. Fullilove, Shreveport, La.

Application July 26, 1946, Serial No. 686,531

1 Claim. (Cl. 33—107)

1

This invention relates to improvements in multiscale rules.

An object of the invention is to provide a rule whereby one unit of measurement may be interpreted in terms of another unit of measurement.

Another object of the invention is to provide a rule having a body with a plurality of architectural scales thereon, and a rotatable member carried by said body with a plurality of engineering scales thereon, and movable alignment means which when moved into registry with a graduation on one of said scales, indicates related graduations on one or more of said other scales.

A further object of the invention is to provide a rule having a hexagonal faced prism rotatably disposed in a housing, with graduations on each face of the prism, and having a micrometrically movable slider on said housing, which slider is movable longitudinally relative to said prism.

Still another object of the invention is to provide a precision rule of the type described, which is simple in construction, is easily and inexpensively manufactured.

Other objects and advantages of the invention will become apparent from the following description of a preferred embodiment thereof as illustrated in the accompanying drawings, and in which,

Figure 1 is a plan view of my improved rule,

Figure 2 is a side elevation of the rule shown in Figure 1,

Figure 3 is a longitudinal sectional view of the rule shown in Figure 1,

Figure 4 is a left hand end in elevation of the rule shown in Figure 1,

Figure 5 is a transverse vertical section taken on line 5—5 of Figure 2,

Figure 6 is a transverse vertical section taken on line 6—6 of Figure 2,

Figure 7 is a view of scales on the right hand side of the rule, that is, at the upper part of the rule as shown in Figure 1,

Figure 8 is a view of scales on the left hand side of the rule, that is, at the lower part of the rule as shown in Figure 1, and

Figure 9 is a developed view of the engineering scales on the hexagonal prism carried in the rule.

Reference is now had to the drawings, in which like reference characters denote similar parts throughout the several views. As shown, there

2

is a rule body 2, which may be made of wood, celluloid, or other suitable material, and is of any length suitable for the purpose, such as twelve inches, eighteen inches, twenty-four inches, or even longer. The rule body 2 has parallel upper and lower surfaces 4 and 6, with upwardly convergent right and left hand sides 8 and 10, respectively, as shown in Figures 4, 5 and 6.

An elongated strip 12 is secured to the right hand side surface 8 of the rule body 2, and a similar strip 14 is secured to the left side surface 10 of the rule body, both strips being substantially as long as the rule body itself, and formed of a material which may be readily provided with highly visible graduations along its outer surface. On the outer surface of right side strip 12 are formed four longitudinal scales 16, 18, 20 and 22 shown in Figures 7 and 1. These four scales are architects' scales $\frac{3}{8}$ and $\frac{1}{2}$; $\frac{1}{8}$ and $\frac{1}{4}$; $\frac{3}{8}$ and $\frac{3}{4}$; and $\frac{1}{2}$, respectively. On the outer surface of left side strip 14 are formed four longitudinal scales 24, 26, 28 and 30 shown in Figures 1, 2 and 8. These scales are architects' scales 1; $1\frac{1}{2}$ and 3; and 16, respectively; and a metric centimeter scale at the bottom, the last scale being drawn to a scale of one inch to 2.54 centimeters. As best seen in Figure 6, the side strips 12 and 14 have longitudinal tongued side edges 32, 34, 36 and 38, for a purpose to be explained below.

Scale 16 has $128\frac{3}{2}$ " and $64\frac{1}{8}$ " marked graduations or a total of 512 divisions. Scale 18 has $96\frac{1}{8}$ " and $48\frac{1}{4}$ " marked graduations or a total of 576 divisions. Scale 20 has $32\frac{3}{8}$ " and $16\frac{3}{4}$ " marked graduations, or a total of 384 divisions. Scale 22 has $24\frac{1}{2}$ " marked graduations or a total of 576 divisions. Scale 24 has $12\frac{1}{16}$ " marked graduations or a total of 576 divisions. Scale 26 has $8\frac{1}{16}$ " and $4\frac{3}{8}$ " marked graduations or a total of 384 divisions. Scale 28 has $12\frac{1}{16}$ marked graduations or a total of 192 divisions. The centimeter scale 30 has $30\frac{1}{2}$ marked graduations to the 12 inch rule. Each marked graduation is divided into ten equal divisions, making a total of 305 divisions to the 12-inch rule.

The rule body 2 has a longitudinal groove or slot 40 in its upper surface 4, which communicates with a longitudinal bore 42. It will be observed that the slot 40 is as long as the rule body.

2. However, the bore 42 is reduced at its ends 44 and 46, for the reception of the reduced cylindrical journal portions 48 and 50 at the ends of a hexagonal prism 52 which is thereby rotatably mounted. A turning knob 54 has its shank 56 threaded into the end 50 of the prism member 52, and has its head knurled to permit convenient turning of the prism member 52 about its longitudinal axis.

The prism member 52 has six sides 56, which 10 may be successively viewed through the slot 40 as the prism 52 is turned by means of the knob 54. Architects' scales 58, 60, 62, 64, 66, and 68, shown developed in Figure 9, are formed on the faces 56 of the prism member 52, so that by turning the prism about its axis, any desired architects' scale may be viewed from above, through the slot 40, as shown in Figures 1 and 6.

All the scales have their zero point to the left as seen in Figure 1, and thus read from left to right in the view, and all zero points are in alignment transversely of the rule.

A bottom plate 70 has its upper surface 72 spaced from the lower surface 6 of the rule body, as may be seen in Figures 5 and 6, so as to provide a passageway 74 as wide as the rule body and extending substantially the entire length of the rule body, as best seen in Figures 3 and 5. The bottom plate 70 is secured to the rule body by means of metal end fasteners 76 and 78 which are held in place by means of screws 80.

The passageway 74 extends from the point 82 to the point 84 as shown in Figure 3, thereby defining body portions in which bores 86 and 88 are formed to provide journals or bearings for the reception of the reduced unthreaded ends of a micrometric transversing screw 90 extending through the passageway 74 longitudinally of the rule body, and which has an adjusting knob 92 secured on its protruding end which is best seen in Figures 2 and 3. A micrometric screw slide bar 94 has its enlarged central portion 96 slidable in the longitudinal grooves 98 and 100 formed in surfaces 6 and 72 respectively of the rule body and base plate 70. The slide bar 94 also has arms 102 and 104 integral with the central portion 96 and extending laterally in opposed directions therefrom as shown in Figure 5, the arms 102 and 104 extending out of the passageway 74 and being provided at their protruding end portions 106 and 108 with grooves 110 and 112 respectively, for slidable engagement with the lower tongues 38 and 34 of the scale bearing side plates or strips 12 and 14.

The central portion 96 of the slide bar 94 has a threaded bore 94' for the threaded reception of the transversing micrometric screw 90, whereby turning of the screw 90 by means of the knob 92 will cause the slide bar 94 to traverse the passageway 74 longitudinally of the rule body. Movable right and left hand side marker members 114 and 116, respectively, are secured at their lower ends 118 and 120, respectively, to the protruding end portions 106 and 108 of the arms 102 and 104, and may be made integral therewith. The marker members 114 and 116 are parallel to the graduated scale strips 12 and 14, and have transparent windows 122 and 124, respectively, with hair-lines 126 and 128, respectively, marked on the windows as shown in Figure 1. V-shaped notches 130 are formed in the lower ends of the marker members 114 and 116. The graduations on the surfaces 12 and 14 may thus be viewed through the windows 122 and 124, and exact

alignment with the graduations obtained by means of the hair-lines on the windows.

There are a pair of top surface plates 132 and 134 secured on each side of the slot 40 on the upper surface 4 of the rule body, and a transparent elongated window 136 is set into recesses in the edges of the members 132 and 134, so as to bridge across the slot 40, as shown in Figure 6. The sides of the plates 132 and 134 are tongued at 138 and 140. A bridging member 142 connects the upper ends of the side marker members 114 and 116, and extends across the top surface of the rule as seen in Figures 1 and 5. This member also has a transparent window 144 over the slot 40 with an appropriate hair-line, to permit viewing and alignment with the graduations on the prism member 52.

The members 96, 102, 104, 114, 116 and 142 thus constitute the movable slider 146 of the rule, and may be formed of a single piece of material insofar as this is possible. A stationary zero position slider 148, comprising only three portions, namely side portions 150 and 152, and top bridging portion 154, may be fixed in position at the zero points as best seen in Figures 1 and 2, the slider 148 being provided with transparent hair-lined viewing windows similar to the movable slider. However, the stationary slider is preferably made small enough in its outside dimensions, as to allow the movable slider to pass over it in either direction so that when the movable slider is in the zero position the hair-lines of the movable and stationary sliders coincide. A pen or pencil point may be inserted into the notches 130 to mark off the reading desired. Magnifying glass may be used in the transparent windows if desired, to increase visibility. To move the movable slider 146, it is only necessary to turn the knob 92 in the appropriate direction.

It is thus apparent that I have disclosed a rule that is simple in construction, and versatile and accurate for use by engineers, architects, designers and others.

Although I have described a preferred embodiment of my multiscale rule, it is to be understood that various changes may be made in size, shape, materials and arrangement without departing from the spirit and scope of the invention as claimed.

I claim:

A rule comprising a rule body having parallel upper and lower surfaces, and upwardly convergent left and right side surfaces, stationary scales on said side surfaces, said rule body having a bore extending longitudinally therethrough with an elongated viewing slot communicating between said bore and the upper surface of said rule body, a hexagonal prism rotatably disposed in said bore, means at one end of said prism for rotating the same, scales on the faces of said prism, whereby any scale on said prism may be viewed by turning said prism to bring the corresponding face thereof into registry with said viewing slot, a base plate secured at its ends to said rule body and spaced from said body intermediate its ends to form a passageway open along the sides of the rule body and extending longitudinally thereof, a movable slide having a lower portion extending through said passageway and having side portions with viewing windows formed therein lying against said side surfaces of the rule body outside of said stationary scales thereon, said movable slide having a top portion thereof bridging across the said viewing slot, with a viewing window in said top

portion, a traversing screw extending longitudinally through said passageway and journaled at its ends in portions on said rule body, said screw threadedly engaging a portion of said movable slide in said passageway, whereby upon rotation 5 of said traversing screw, said movable slide may be moved longitudinally of said rule body, said movable slide having hair-line means for alignment with a graduation of any of the scales, for interpretation thereof in terms of any other scale 10 on the rule.

DIXIE L. FULLILOVE.
